MATERIAL SEPARATOR

Richard D. Nichols, Columbus, Ohio, assignor to
The Jeffrey Manufacturing Company, a cor-
poration of Ohio

Application August 18, 1936, Serial No. 96,643

2 Claims. (Cl. 209—496)

This invention relates to a jig and more particularly to automatic means for controlling the depth of the refuse bed formed on the screen of a jig.

5 An object of the invention is to provide a completely automatic refuse depth responsive means for controlling the depth of the refuse bed on the screen of a jig, with a minimum expenditure of power.

10 A more specific object of the invention is to provide a float control refuse ejector for a jig in which the float controls a valve, which valve controls hydraulic means for determining the rate of ejection of refuse.

15 Other objects of the invention will appear hereinafter, the novel features and combinations being set forth in the appended claims.

In the accompanying drawings,

Fig. 1 is a side elevational view of a jig comprising my invention with parts broken away in the interest of clearness;

Fig. 2 is a front end elevational view of the device of Fig. 1 with parts broken away in the interest of clearness;

25 Fig. 3 is an enlarged detail elevational view of the float control valve and ejector operating mechanism comprising my invention;

Fig. 4 is a sectional plan view taken on the line 4—4 of Fig. 3 looking in the direction of the 30 arrows;

Fig. 5 is a sectional detail view taken on the line 5—5 of Fig. 4 looking in the direction of the arrows;

Fig. 6 is a sectional detail of the valve taken 35 on the line 6—6 of Fig. 4 looking in the direction of the arrows;

Fig. 7 is a side elevational view of the operating mechanism for the rotary ejector valve;

Fig. 8 is a sectional view taken on the line 8—8 40 of Fig. 7 looking in the direction of the arrows; and

Fig. 9 is a diagrammatic illustration of the hydraulic system for controlling the rotary refuse 45 ejector mechanism.

45 Briefly described, the main portion of the jig comprises a main frame 10 formed by longitudinally extending channel members 11, to which are rigidly attached transversely extending channel members 12, to each of which are attached 50 upwardly extending angle members 13. The main frame 10 supports the longitudinally extending tank 14 which is divided into two compartments 15 and 16 which, except for obvious differences, are of substantially the same construction. It will be evident that the number of

compartments may either be reduced to one or increased above two to any desired number. The tank 14 is provided with a feed chute 17 which directs raw coal into compartment 15 and within a discharge chute 18 which directs the clean 5 coal from compartment 16.

Within each of the compartments 15 and 16 is provided a screen 19 carried upon an appropriate adjustable frame 20 which is pivoted at the forward end upon a transversely extending 10 shaft 21 and is supported by a pair of adjustable hangers 22 at its rear end. It will thus be evident that by adjusting the hangers 22, the slope of the screen 19 may be adjusted to determine the rate of travel of material thereover. 15

Adjacent the lower end of the screen 19 there is an opening 23 formed by a vertically adjustable plate 24 carried by a baffle or weir 25 which separates the compartments 15 and 16. The opening 23 leads to a chute 26 which directs refuse 20 to a rotary paddle wheel type refuse discharge valve 27. The chute 26 includes a pivoted plate 28 carrying an arcuate contact plate 29 provided with a weight 30. In normal operation the arcuate plate 29 will contact the blades of the valve 25 27, but should an unusually large piece of refuse be caught therein it will move as provided by the pivoted plate 28 and permit the large particle to pass through said valve 27.

The valve 27 will discharge refuse into the 30 boot 31 of an elevator mechanism 32 by which the refuse will be elevated and discharged from the jig through a chute 33.

To drive the two elevator mechanisms 32, 32 I provide an electric motor 34 and an appropriate 35 drive gearing 35 whereby both of said elevator mechanisms 32, 32 will be operated from the same motor.

To provide for supplying water to the compartments 15 and 16 there is provided a longitudinally 40 extending water pipe 36 with an individual valve 37 leading to each of the compartments 15 and 16. Each of said compartments 15 and 16 is also provided with a bottom comprising a 45 reciprocating diaphragm 37 in the form of a cylindrical plate which is connected to an inwardly extending stationary plate 38 provided with a circular opening. A flexible ring 39, preferably of rubber, connects the edges of the 50 plate 38 and the diaphragm 37 to provide a watertight bottom for each of said compartments 15 and 16 while permitting reciprocatory movement of the diaphragm 37. It is to be noted that the plane of the diaphragm 37 is substantially 55

parallel with the plane of the screen 19 in its normal position of adjustment.

To provide for the reciprocation of the diaphragms 37, 37 of the two compartments 15 and 16 each of said diaphragms is provided with a piston rod 40, the end of which is connected to a piston in a cylinder 41. The cylinder 41 is provided with air under pressure by a conduit 42 which acts on the mentioned piston to counter-balance the normal weight of the liquid on the diaphragm 37. Also attached to each diaphragm 37 is a connecting rod 43 which is adjustably attached to a rocker arm 44 which is pivoted to a bracket 45 carried by a pair of channel members 46, which channel members 46 also support the cylinder 41. The connecting rod 43 is mounted in a slide block 47 which may be adjusted upon the rocker arm 44 to adjust the stroke of the diaphragm 37.

20 The rocker arm 44 is provided with a cam roller 48 adapted to ride between the outer and inner tracks of a cam 49 carried upon a shaft 50. The two shafts 50 will be interconnected by a chain and sprocket mechanism 51 which is provided with a chain tightening mechanism 52.

To drive the two shafts 50 and thus to reciprocate the two diaphragms 37, there is provided a single electric motor 53 which drives one of the shafts 50 directly through speed reduction gearing 54. (Fig. 2.) It will thus be evident that means are provided to reciprocate the two diaphragms 37 through repeating cycles of operation as determined by the formation of the cams 49. These cams may be of the same or different shapes for the two compartments 15 and 16, and may be operated either in synchronism or out of phase. It is preferred that they operate 180 degrees out of phase thereby to equalize the load upon the motor 53. It is also to be noted that the stroke of each of the diaphragms 37, 37 may be individually adjusted. It is thus possible to give separate and individual treatment to the bed of material in each of the compartments 15 and 16 which is particularly desirable in view of the fact that the beds of material are inevitably of different composition in the two compartments.

Attention is now directed more particularly to Figs. 4 to 9, inclusive, of the drawings and to the improved and sensitive control means for the refuse discharge valve 27, comprising my invention. Mounted upon a transversely extending angle member 55 for each of the compartments 15 and 16, which is supported by the longitudinal sides of the tank 14, are a pair of brackets 56 and 57. The bracket 56 is provided with a pair of vertically spaced sleeves 58 and 59 (Fig. 3), and the bracket 57 is provided with a sleeve 60, the axis of which is in alignment with the axis of sleeve 58. (Fig. 4.) Between the sleeves 58 and 60 and extending through each of them is a composite shaft 61 formed by stub shafts 62 and 63 interconnected by a hollow pipe 64. Stub shaft 62 is mounted in anti-friction bearings 65 in the sleeve 58 and stub shaft 63 is mounted in anti-friction bearing 66 in sleeve 60. A stub shaft 67, somewhat similar to stub shaft 62, is also mounted in appropriate anti-friction bearings in sleeve 59.

70 Extending forwardly from and rigidly attached to the stub shafts 62 and 67 is a pair of parallel arms 68 and 69 respectively, which form part of a parallel motion mechanism for supporting a float 70. The float 70 is of stream-line form and 75 is adapted to be totally submerged by the jiggling

fluid of the jig. It is provided with an integral top post 71 to which is attached an upwardly extending stream-line pipe 72 provided with adjusting apertures 73 and attaching shafts 74 and 75 which are mounted in receiving sockets carried by the arms 68 and 69 respectively, by anti-friction bearings. The pipe 72 also carries a pointer 76 which cooperates with a stationary scale 77 carried by bracket 56, to indicate the average position of the float 70. A rod 78 adapted to receive adjustable weight washers 79 is also carried adjacent the top of the pipe 72. By removing or replacing washers 79 the effective weight of the float 70 may be adjusted. It will be evident that the elements just described provide a parallel motion mechanism whereby the movement of the float 70 will be transmitted to the shaft 61 and the position of said shaft 61 is employed to control the rate of discharge of refuse by controlling the rate of rotation of the 20 refuse discharge valve 27.

It is to be particularly noted that all friction surfaces in the float control mechanism are mounted upon anti-friction bearings, thus providing for a very sensitive float mechanism. I 25 employ this very sensitive float mechanism merely to control a valve which, of course, will require a minimum of energy, thus maintaining at a maximum the sensitivity of said float mechanism. 30

As best seen in Figs. 4, 5 and 6, the control valve is provided by inserting a bushing 80 over the stub shaft 63 and into the sleeve 60. The bushing 80 is provided with an enlarged key-way 81 (see Fig. 5) with which a key 82 carried by 35 stub shaft 63 cooperates. It is to be noted that the key 82 does not fit tightly in the key-way 81 and thus a limited amount of up and down motion of the float 70 is permitted without requiring corresponding rotation of the sleeve 60. This 40 permits the normal up and down motion of the float 70 incident to the pulsations of the jiggling fluid without affecting the refuse discharge mechanism. It is thus evident that the bushing 80 will take an angular position determined by 45 the normal average position of the float 70.

The bushing 80 is also provided with a pair of grooves 83 and 84 which are separated by integral bosses 85 and 86. Formed in the bushing 80 are four ports, 87, 88, 89 and 90. To port 87 is connected a pipe 91 leading to the oil reservoir 97 of the fluid pressure system. To port 88 is connected a pipe 92 leading to the top of a control cylinder 95. To port 89 is connected a pipe 93 leading to the pressure side of an oil pump 96 which may be a gear type pump. To port 90 is connected a pipe 94 leading to the bottom of the cylinder 95. (See Figs. 1 and 5.) 50 55

In the normal position of adjustment of the control valve, as illustrated in Fig. 6, the ports 60 88 and 90 will be sealed by the bosses 85 and 86, thus maintaining the piston 98 in cylinder 95 in whatever position it has been moved to. At the same time fluid in the pipe 93 will be shut off and the pump 96 will operate merely to pump fluid 65 into the reservoir 97 through the high pressure relief valve 99, seen particularly in Fig. 9 of the drawings.

In the float 70 is lifted in response to a predetermined large accumulation of refuse on the 70 screen 19, the bushing 80 will rotate in a clockwise direction, as viewed in Fig. 6, resulting in the establishment of communication between the pipes 92 and 93 and between the pipes 91 and 94 through the grooves 84 and 83, respectively. As 75

a consequence pressure will be supplied to the top of the piston 98 in cylinder 95 to move the piston downwardly while the bottom of said piston is connected to the oil reservoir 97. This movement will continue so long as the bushing is in said rotated position. If said bushing 80 is rotated in a counter-clockwise direction by the lowering of the float 70, then communication will be established between the pressure pipe 93 and the pipe 94 leading to the lower side of piston 98 and communication at the same time will be established between pipes 91 and 92. As a consequence, the piston 98 will be elevated in the cylinder 95.

15 It is therefore obvious that the position of the piston 98 will be adjusted whenever the float 70 moves from its normal position. The movement of said piston 98 is employed, as hereinafter described, to control the rate of discharge of the 20 refuse, by controlling the rate of rotation of the refuse discharge valve 27.

It may also be noted that upon the end of the 25 stub shaft 63 there is carried a pendulum mechanism 100 (Figs. 1 and 3) to stabilize the action of the float 70.

Attention is now directed particularly to Figs. 1, 7 and 8 and to the mechanism for rotating the refuse discharge valve 27 under the control of the piston 98. It may first well be noted that 30 the cylinder 95 is pivotally mounted upon a bracket 101 carried by a side wall of the tank 14 to provide free pivotal movement of said cylinder 95. The piston 98 is provided with a piston rod 102 and with a packing gland 103 to insure an 35 oil-tight head-end compartment for the cylinder 95. Piston rod 102 connects to a rod 104 by a turnbuckle mechanism 105, thereby providing an adjustment for the effective length of the arm formed by rods 102 and 104. Rod 104 is pivoted 40 to a bracket 106 carried upon arms 107, 107 provided with counter-weights 108 and supported upon inner bearings of a bracket 109 supported by screws 110 upon a removable plate 111, which plate is carried by the side wall of tank 14. The 45 plate 111 is provided with a journal bearing 112 for a shaft 113 of the refuse discharge valve 27. The shaft 113 is also journaled in spaced journals provided by the bracket 109. By removing the bracket 109 and the plate 111, the refuse 50 discharge valve 27 may be removed from the tank 14 as a unit by moving it laterally therefrom. (See Fig. 8.)

Keyed to the outer end of the shaft 113 is a ratchet wheel 114 which, upon being rotated, will 55 rotate said shaft 113 and thus rotate the refuse discharge valve 27. To oscillate the ratchet wheel 114 I provide a continuously operating bell crank lever 115 which carries a pair of engaging pawls 116, and which is continuously oscillated 60 by a rod 117 which is reciprocated by a crank 118 (see Fig. 1) driven from shaft 50 through appropriate speed reduction mechanism 119.

To control the extent of rotation of the refuse discharge valve 27 upon each oscillation of the 65 bell crank 115, the bracket 106 carries a pawl controlling shield 120 which determines by its position the angular movement of the ratchet wheel 114 for each oscillation of the bell crank 115. The system is preferably so adjusted that in normal 70 operation there will be some movement of the ratchet wheel 114 for each oscillation of the bell crank lever 115 and this angular movement is either increased or decreased as required by the depth of the refuse bed to maintain said 75 depth substantially constant. That is, if the

refuse becomes deeper than normal, the float 70 will be effective to adjust the shield 120 so that upon each oscillation of the bell crank lever 115, the refuse discharge valve 27 will move through a greater angle and thus discharge refuse at a 5 more rapid rate. When the depth of the refuse bed is returned to normal, the shield 120 will be moved by the float 70 so that the refuse discharge valve 27 moves through a normal angle for each oscillation of the bell crank lever 115. If 10 the refuse bed becomes of an undesirably low depth then the shield 120 will be controlled by the float 70 so that the refuse discharge valve 27 only moves through a very small angle for each oscillation of the bell crank lever 115 and in an 15 extreme case the shield 120 would prevent any rotation whatever of said valve 27 by the bell crank lever 115.

In the operation of the device comprising my invention the raw coal to be cleaned by the removal of the refuse, such as pyrite, shale and bony coal, from the pure coal, is fed to the feed chute 17 leading to compartment 15 of the jig. The tank 14 will, of course, be supplied with a proper amount of water and the diaphragms 37 20 of compartments 15 and 16 will cause a pulsing movement of the liquid upwardly and downwardly through the screens 19. As a consequence, the raw coal will be first stratified in the compartment 15 with the refuse, and particularly the 25 shale and pyrite, on the bottom, and the clean coal and bony coal stratified on top. The refuse ejector mechanism 27 of the compartment 15 will be adjusted with a view of removing practically all of the shale and pyrite and possibly some of 30 the bony coal. The stratified clean coal and bony coal will then pass into the compartment 16, while remaining in a stratified condition, where it will be more completely stratified with the bony coal on the bottom and the clean coal on top. 35 The refuse ejector valve 27 of compartment 16 will be so operated as to remove the stratified bony coal while the clean coal is discharged over 40 discharge chute 18.

The float 70 in each compartment 15 and 16 45 will be so adjusted as to maintain a position substantially on top of the stratified refuse which is to be removed, and due to its very sensitive construction will operate to control the rate of discharge of a rotary discharge valve 27, to maintain the depth of the refuse bed in each compartment at a predetermined value. As a consequence, the jigging conditions in each of the compartments 15 and 16 will be uniform, resulting in a very efficient separation of the coal and 50 refuse. This uniform condition will be maintained in an entirely automatic manner and by my improved system, which is of extreme sensitivity due to the fact that the work required to be done by the float 70 is maintained at a minimum, 55 namely, that of merely operating a control valve. It is thus seen that a very efficient and entirely automatic jig has been provided for cleaning coal.

While coal is the principal material for which my jig is designed, it is evident that it may be 60 employed to separate other materials which differ in specific gravities.

Obviously those skilled in the art may make various changes in the details and arrangement of parts without departing from the spirit and 65 scope of the invention as defined by the claims hereto appended, and I therefore wish not to be restricted to the precise construction herein disclosed.

Having thus described and shown an embodiment 70

ment of my invention, what I desire to secure by Letters Patent of the United States is:

1. In a separator, the combination with a material support, of a totally submerged float, a rotary discharge valve, a reciprocating arm, means for rotating said valve a variable amount upon each reciprocation of said arm including an amount between the maximum and the minimum amounts, said means including a fluid operated rod, a piston controlling said rod, valve means controlling said piston to adjust it to more than two positions, and anti-friction mounted means connecting said float and valve means.
2. In a separator, the combination with a material support, of a rotary valve for discharging refuse which accumulates on said support, means including a totally submerged float for measuring the depth of refuse on said support, means for substantially continuously rotating said valve to

discharge refuse substantially continuously, a hydraulic control system controlled by said float and controlling the rate of rotation of said valve, said control system comprising means providing a source of substantially non-compressible fluid under pressure, a cylinder having a piston therein, entry ports at opposite ends of said cylinder, said piston being connected to means to adjust the rate of rotation of said rotary valve, a control valve for said cylinder operable by said float, 10 said control valve being so constructed and arranged that when in its normal position said piston will be locked in position by trapping said non-compressible fluid on opposite sides thereof in an inert condition and when moved to opposite 15 sides of said normal position said fluid under pressure will act on said piston to move it in opposite directions.

RICHARD D. NICHOLS.
